GARMENT OR IRONING PRESS

Ernest Davis, Syracuse, N. Y., assignor to The Prosperity Company Inc., Syracuse, N. Y., a corporation of New York

Application July 3, 1929, Serial No. 375,681
Renewed May 10, 1934

34 Claims. (Cl. 68—9)

This invention relates to pressing machines, such as garment, ironing and laundry presses, and has for one of its objects, a particularly simple and efficient actuating or motion transmitting mechanism including an automatic following up mechanism which causes the press to deliver uniform maximum or predetermined pressure with a given actuating force without adjustments, regardless of the thickness of the work 5 and of the padding on one or both of the pressing elements, and regardless of the amount of compression of, or settling of, the padding.

Another object of the invention is to devise a new and novel actuating mechanism for a garment or ironing press including two motors in which one motor is controlled by manually operable control means and the other motor is controlled automatically upon a predetermined extent of movement thereof.

20 The invention consists of the novel features and in the combinations and constructions hereinafter set forth and claimed.

In describing this invention reference is had to the accompanying drawings in which like characters designate corresponding parts in all the views.

Figures 1 and 2 are side elevations of pressing machines embodying slightly different exemplifications of my invention.

30 Figures 3 and 4 are enlarged fragmentary rear and side elevations of the toggle links and booster lever.

Figure 5 is a sectional view, partly diagrammatic, of the operator-operated controls for the 35 actuating mechanism, the motors or pistons and cylinders for closing the press under initial and final pressure being also shown.

Figures 6, 7 and 8 are views, similar to Figure 5, of modified connections of the control shown 40 in Figure 5.

Figures 9 and 10 are views similar to Figures 4 and 5 of a modified form of the parts seen in Figures 3 and 4.

This invention comprises generally, an actuating or motion transmitting mechanism for the movable element or jaw of a garment or ironing press comprising two sections, one of which acts to close the press from wide open position to closed, or nearly closed position, or to close the 45 press under light pressure, that is, light pressure compared with final heavy pressure, or to initially or preliminarily close the press, and the other of which boosts the pressure through the former section or a portion thereof, after the press has 50 been initially closed. The pressure delivered un-

der comparatively light pressure is usually the maximum pressure that can be applied by the motor means before the resistance to the head overcomes the motor means, just prior to the booster operation. 5

More specifically, the actuating or motion transmitting mechanism comprises a toggle for closing the press and means for boosting one of the links of the toggle preferably, the link connected to the movable pressing element or head 10 after the toggle has straightened as far as it can straighten under conditions such as thickness of the work, padding, etc., said link being connected to the other toggle link to have an endwise movement relatively thereto during the boosting operation. 15 The boosting operation may take place in any nearly straightened position the toggle assumes. The toggle does not have to be in its dead center line during the boosting operation as means is provided for preventing folding up 20 action or retrograde action of the toggle during the boosting operation.

I have here illustrated my invention as embodied in a conventional type of garment and laundry press in which the cooperating pressing 25 elements or jaws are a head 1 movable toward and from a buck 2, the latter being mounted upon the frame 3 of the machine. The head 1 is supported by the usual lever 4 pivoted at 5 between its ends to a standard 6 rising from the 30 frame.

The motion transmitting mechanism, in addition to the lever 4, comprises toggle links 7 and 8 pivoted together at 9, the link 7 being pivoted at its upper end at 10 to the rear arm of the 35 lever 4 and the link 8 being pivoted at its lower end at 11 to the base of the frame.

In the illustrated embodiment of my invention, the toggle is straightened by suitable motor means and preferably the motor means is pressure operated and is here shown as a cylinder 12 having a piston 13 therein, the rod 14 of which is pivoted at 15 to the front end of an arm 16 forming an angle lever with the link 8. The cylinder is pivoted at 17 to the frame to have an oscillating 45 movement during the opening and closing of the press.

The link 7 is connected to the link 8 to have an endwise or thrusting movement relatively thereto and the pivot or knuckle pin 9 is here 50 shown as extending through a lengthwise slot 18 in the lower end of the link 7. The slot permits the relative endwise or boosting movement of the link 7.

The means for closing the press under final 55

pressure comprises a booster, cam bar, or pry lever 19 pivoted at 20 to the frame (Figure 1) and extending rearwardly and having its rear end arranged to coact with a shoulder 22 on the link 7 after the press is initially closed, or the toggle is in substantially straightened position or straightened position. The shoulder is obviously out of juxtaposition with the booster lever 19 when the press is open and the toggle folded, and 10 is movable into juxtaposition to the lever 19 as the toggle straightens.

The lever 19 is provided with a face 21 at its rear end extending in a general direction concentric with the arc A—A of movement of the joint 15 9 of the toggle and being normally so located that the shoulder 22 on the link 7 slightly clears the face during the straightening operation of the toggle.

As here shown, the shoulder or bearing surface 20 22, provided at the lower end of the link 7 or on the bearing of the link 7 which receives the pivot or knuckle pin 9, and also the face 21 is so formed as to prevent retrograde movement of the toggle during the boosting or prying action of the lever 17. As here illustrated, the shoulder 22 and 25 face 21 are provided with small interlocking toothed or rough coacting faces 220, 210.

As seen in Figures 9 and 10, instead of interlocking or rough toothed surfaces, the link 7 30 and the lever 19 may be provided with coacting wedge means in the form of a groove 70 provided on one of the coacting parts as the lower end of the link 7, and the pry lever 19 may be formed with a complementary wedge shaped rib 190. The 35 rib and the groove normally slidably fit together so that there is no lost motion to take up to wedge or lock the parts together when the pry lever commences to act.

The groove 70 and the wedge 190 are arc shaped 40 and extend in arcs substantially concentric with the arc of movement to the knuckle joint of the toggle.

In Figure 1, the lever 19 is shown as pivoted at 45 its forward end and the power for actuating it applied thereto near its rear end.

In Figure 2, the corresponding lever 19a is pivoted between its ends at 20a and the power is applied from the front end of the lever. The power is applied to the booster lever in either 50 case by motor means, preferably a pressure operated motor as a cylinder 23 and piston 24 movable therein, the rod 25 of which is connected either directly or through motion transmitting mechanism to the booster lever.

55 In the construction shown in Figure 1, the piston rod 25 is connected to a rock arm 26 mounted on a shaft 27 journalled in a bracket on the frame and having a cam 28 thereon which coacts with a pin or follower 29 on the booster lever 19.

60 In Figure 1, the cylinder 23 is pivoted at its lower end at 30 to the frame below the lever 19 and the piston moves upwardly on its power stroke.

In the form shown in Figure 2, the piston rod 65 25a of the piston movable in the cylinder 23a is pivoted directly to the front arm of the lever 19a.

The pistons 13 and 24 are single acting and the press is opened by countersprings 31 when the pressure in both cylinders is released.

70 The flow of motive fluid, as compressed air, to and from the cylinder 12 is controlled in any suitable manner and neither the motor nor the control means per se, forms part of this invention and the toggle links 7 and 8, and the pry lever or booster lever 19 may be actuated in any suit-

able manner, as long as the motors are operated successively.

The control means here shown comprises a valve casing 32 having a normally closed spring 5 pressed intake valve 33 and a normally open exhaust valve 34 therein, these being connected by a stem 35 so that they act as a unit, and operating means therefor. The intake end of the valve casing 32 is connected to a pipe 36 leading from any suitable source of supply of motive fluid. 10 The valve casing 32 is connected at a point between the valves 32, 34 to a pipe 37 leading to a coupling 38 opening into an intake port 39 at the upper end of the cylinder 12. The valves 33, 34 are operated by manual means as a push 15 button 40, and the motion of the push button is transmitted through a lever 41 and an intermediate lever 42 to the stem 43 of the exhaust valve 34.

The action of the lever 41 by the push button 20 is against the action of a returning spring 44. Obviously, upon depression of the push button 43, motive fluid, as air, is free to flow from the feed line 36 through the valve casing 32, pipe 37 to the cylinder 12 and when these valves are 25 in their normal position, air is free to exhaust from the cylinder 12, through pipe 37 and valve casing 32. The valves are locked in their operated position by pressure operated means as a diaphragm chamber 45 having a diaphragm 46 30 therein, the pressure side of the diaphragm chamber being connected by a pipe 47 to a coupling 48 in a pipe 49 which communicates with a valve casing 50 on the side of the cylinder, this valve casing having a port 50a opening into the 35 cylinder in position to be uncovered or passed by the piston 13 when the piston approaches the end of its power stroke. When this occurs, air pressure passes from the cylinder back through the pipes 49, 47 to the diaphragm chamber 45 40 to actuate the diaphragm 46 therein and the movement of the diaphragm is transferred through a sliding stem 51 to the intermediate lever 42 and thus locks the valves 33, 34 in their 45 operated position.

In order to require both hands of the operator to be used when closing the press, a second push button or manual 52 is provided which, through levers 53, 54 corresponding to the levers 41, 42 acts on the stem 55 of a normally open exhaust 50 valve 56 in a valve casing 57, this casing being connected by a pipe 58 to the coupling 38. This exhaust valve 56 is held in its operated position by a diaphragm chamber 59 having a diaphragm 60 therein acting on a sliding stem 61 which 55 thrusts against the intermediate lever 54.

The pressure side of the diaphragm chamber 59 is connected by a pipe 62 to the coupling 48. Obviously, both push buttons 40, 52 must be depressed and held depressed while the press is 60 closing and when the press is closed, or the piston 13 passes the port in the casing 50, both valves will be locked in closed position by reason of the air passing back from the cylinder to the pipes 47, 62 to the diaphragm chambers. If the 65 push button 52 only is depressed, nothing will happen, because the intake valve 32 will remain closed. If only the push button 40 is depressed, the air will pass from the coupling 38 out past the exhaust valve 56 in the casing 57. Hence, to 70 effect the closing of the press, both push buttons 40 and 52 must be depressed.

To open the press, the air is exhausted from the diaphragm chambers 45, 59 by means of a 75 normally closed spring pressed exhaust valve 63

in a valve casing 64 which is connected by a pipe 65 into any pipe communicating with the diaphragm chambers. It is here shown as connected to the pipe 62. The exhaust valve is operated by 5 a trip or release lever 66, this being grouped with one or the other of the push buttons 40, 52.

The controls for the motor which actuates the booster lever 19 or 19^a comprises, an automatically operated valve consisting of a casing 67 having a normally closed spring pressed intake valve 68 and a normally open exhaust valve 69 therein, the two valves being connected by a stem 70, so that they act as a unit. These valves are operated automatically by pressure operated means 10 as a diaphragm chamber 71 having a diaphragm 72 therein which acts on a sliding stem 73 thrusting against one arm of a lever 74, the other arm of which thrusts against the stem 75 of the exhaust valve 69.

20 The pressure side of the diaphragm chamber is connected by a pipe 76 to any pipe controlled by the port in the valve casing 50. It is here shown as connected to the pipe 47 leading to the diaphragm chamber 45. Obviously, after the 25 press is preliminarily closed by the depression of both push buttons 40, 52, the air pressure will pass back from the cylinder 12 after the piston 13 clears the port in the casing 50, the air passing through the pipe 47 to lock the valves in the casings 32 and 57 in their operated position and also, through the pipe 76 to the diaphragm chamber 71 to operate the valves in the casing 67 to permit the air to flow to the cylinder 23 to actuate the booster lever 19.

35 Upon operation of the trip or release lever 66, the air will be exhausted from all diaphragm chambers 45, 59, 71 permitting the press to open.

In the operation thus far described, depression of the push buttons 40, 52 straightens the toggle links 7 and 8 until the head 1 comes down on the buck 2, or the work thereon, with pressure and until the pressure is overcome by the resistance of the work and the padding. When this occurs, the toggle is in any one of a plurality of 45 nearly straightened positions and the follower or shoulder 22 is over and slightly spaced from the face 21. This occurs shortly after the piston 13 uncovers the port in the casing 50. Thereafter, the air enters the cylinder 23 or 23^a and actuates 50 the pry or booster lever 19 or 19^a to apply final pressure, this being sufficient in all cases to compensate for different thicknesses of the work and compression of the padding, so that a uniform final pressure is delivered regardless of the thickness of the work and the padding and the compression of the padding and without any adjustments or any attention on the part of the operator.

60 In Figure 6, the valve casings 80 and 81 corresponding to the valve casings 32 and 57 are unprovided with locking means or diaphragm chambers and after the press is preliminarily closed and the push buttons 82, 83 corresponding to the push buttons 40 and 52 are released, the air is 65 free to exhaust from the cylinder 12^a which effects the closing of the press and the press is held closed by the pressure in the cylinder 84 corresponding to the cylinder 23.

70 In the construction shown in Figure 6, 85 is a valve casing having a normally closed spring pressed intake valve 86 and a normally open exhaust valve 87 therein, the two valves being connected by a stem 88 so that they act as a unit. The intake end of the casing 85 is connected by 75 a pipe 89 to the supply pipe 90 corresponding to

the supply pipe 36 in Figure 5. The valve casing 85 is connected at a point between the valves 86, 87 by a pipe 91 leading to the intake end of the cylinder 84. The valves 86, 87 are operated by pressure operated means as a diaphragm chamber 92 having a diaphragm 93 therein acting on a sliding stem 94 which acts upon one end of a lever 95, the other end of which thrusts against the stem 96 of the exhaust valve 87.

The pressure side of the diaphragm 92 is connected 10 by a pipe 97 to a valve casing 98 on the cylinder 12^a corresponding to the valve casing 50, Figure 5, which casing has a port, not shown, opening into the cylinder and arranged to be uncovered by the piston when the piston approaches 15 the end of its power stroke. When the port in the casing 98 is uncovered, the air pressure passes back through the pipe 97 actuating the diaphragm 93 and through the sliding stem 94 and lever 95 closes the exhaust valve 87 and opens the intake 20 valve 86, thus permitting air to flow to the cylinder 84 to actuate the booster lever.

The valves 86, 87 are automatically locked in their operated position by pressure operated means as a diaphragm chamber 99 having a diaphragm 100 therein acting on a sliding stem 101 which thrusts against one arm of a lever 102, the other arm of the lever being arranged to coact with the lever 95. The pressure side of the diaphragm chamber 99 is connected by a duct 103 25 to the interior of the valve casing 85. Thus, when the valves 86, 87 are operated by the diaphragm 93 as just described, the motive fluid or compressed air will flow from the chamber 85, through the duct 103 to the diaphragm chamber 99 so 30 that the lever 102 will be actuated to lock the valves 86, 87 in their operated position and thus, lock the press closed.

The air pressure is released from the diaphragm chamber 99 to open the press by a normally closed spring pressed exhaust valve 104 in a casing 105, which casing is connected by a pipe 106 to the pressure side of the diaphragm chamber 99. The exhaust valve 104 is operated by a 40 trip or release lever 107.

In the form shown in Figure 6, both push buttons 82, 83 are depressed to effect the closing of the press and when the piston in the cylinder 12^a passes the port in the casing 85, air pressure will pass into the diaphragm chamber 92 and 50 open the intake valve 86 and close the exhaust valve 87, permitting air to pass from the main supply line 90 to the cylinder 84 and actuate the pry or boost lever 19 or 19^a and also, these valves 86, 87 will be locked in their operated position by 55 the diaphragm 100.

To open the press, the release lever 107 is operated to exhaust the air from the diaphragm chamber 99 and when the air is thus released from the diaphragm chamber 99, the holding 60 force on the lever 102 is released, permitting the valves 86, 87 to return to their normal position under the influence of a spring behind the intake valve 86. When this occurs, air has already been exhausted from the diaphragm chamber 92 65 by reason of the fact that the operator has presumably released the two push buttons 82, 83 so that the air is free to exhaust from the cylinder 12^a and hence, from the diaphragm chamber 92 through the pipe 97 and valve casing 98. 70

In Figure 7, the flow of air to and from the cylinder 12^a is controlled by a valve arrangement similar to that operated by the push buttons 82, 83 shown in Figure 6, but the operation of the valve for controlling the flow of motive fluid to 75

the cylinder 84 which actuates the booster lever 19 or 19^a, is controlled through a check valve 120 connected to the port 98 which opens into the cylinder 12^a when the piston has nearly completed its power stroke, this check valve serving to delay the operation of the piston in the cylinder 84.

108 designates a valve casing corresponding to the valve casing 85, Figure 6, and having a normally closed spring intake valve 109 and a normally open exhaust valve 110 therein connected by a stem 111. The intake end of the valve casing 108 is connected by a pipe 112 to a supply pipe 113 corresponding to the supply pipe 90, Figure 15. The valves 109, 110 are operated by a diaphragm chamber 114 having a diaphragm 115 therein, which, through a sliding stem 116 actuates a lever 117 acting on the stem 118 of the exhaust valve 110.

20 The pressure side of the diaphragm chamber 114 is connected by a pipe 119 to the check valve casing 120 having a spring pressed check valve 121 therein, this casing being connected by a pipe 122 to the port in the valve casing 98 opening into the cylinder 12^a.

When the piston in the cylinder 12^a does uncover the port in the casing 98, the pressure does not immediately pass with its full force to the diaphragm chamber 114 as the pressure is delayed by the operation of the check valve 121 and the pressure must build up in the cylinder 12^a sufficiently to overcome the resistance to the check valve 121 and this delay permits more pressure to be delivered through the toggle links 35 before boosting action begins. When sufficient air has passed the check valve 121 pressure will build up in the diaphragm chamber 114 to operate the intake valve 109 and close the exhaust valve 110. The press is held locked by a normally closed spring pressed exhaust valve 123 in a casing 124 connected by a pipe 125 to the pipe 119. This exhaust valve 123 is operated by a trip or release lever 126.

To open the press after it has been closed as 45 described, the trip lever 126 is operated to exhaust the air from the diaphragm chamber 114 thus permitting air to exhaust from the cylinder 84 and hence permitting the press to be opened by the countersprings.

50 In Figure 8, the control mechanism is quite similar to that shown in Figure 7. The flow of motive fluid to and from the cylinder 12^a is controlled by valves in casings 130 and 131 operated by push buttons 132, 133 similar to the valves in casings 80, 81 and push buttons 82, 83, Figure 6.

The flow of motive fluid to the cylinder 84 is controlled by valves similar to those shown in Figure 7 and located in the casing 108. In Figure 8 a corresponding casing 134 contains a normally closed spring pressed intake valve 135 and a normally open exhaust valve 136 connected by a stem 137 so that they act as a unit. The intake end of the casing 134 is connected by a pipe 138 and coupling 139 to the supply pipe 140. The casing is connected between its ends by a pipe 141 to the intake port of the cylinder 84. The valves 135 and 136 are locked in their operated position by a diaphragm chamber 142 having a diaphragm 143 which, through a sliding stem 144 acts on a lever 145 thrusting against the stem 146 of the exhaust valve 136. The pressure side of the diaphragm chamber 142 is connected by a pipe 147 to a valve casing 148. The valve casing 148 is connected by a pipe 149 to the valve casing 98 on the cylinder, which valve cas-

ing has a port opening into the cylinder 12^a in position to be uncovered by the piston when the piston approaches the end of its power stroke.

The valve casing 148 has a valve 150 therein actuated on by a spring 151 which normally tends to open it. The valve casing also has a diaphragm chamber 152 having a diaphragm 153 therein which acts to hold the valve 150 against its seat against the action of its spring 151. The diaphragm chamber 152 is connected by a pipe 154 to the coupling 139 in the feed line 140. Thus, the diaphragm 153 is normally under pressure to hold the check valve 150 closed. Upon depression of the push buttons 132, 133, the air will flow to the cylinder 12^a to actuate the piston 15 on its power stroke as in the other constructions, and when the piston uncovers the port in the casing 98, the air pressure will pass through the pipe 149 to the valve casing 148 and in conjunction with the spring 151, open the valve 150 20 against the action of the diaphragm 153.

The air passes from the valve casing 148 through pipe 147 to the diaphragm chamber 142 and effects the closing of the exhaust valve 136 and the opening of the intake valve 135, permitting the air to flow to the cylinder 84 and actuate the piston therein to operate the pry lever 19 or 19^a.

The pressure of the spring 151 and the pressure built up in the valve casing 148 through the pipe 149 overcomes the pressure on the diaphragm 153 sufficiently to open the valve 150 and permit the air to flow through the pipe 147 to the diaphragm chamber 142 to operate the valves 135, 136. When this takes place, the operator 35 has presumably removed his hands from the push buttons 132, 133 so that the air is free to exhaust from the cylinder 12^a. Hence, there is no pressure assisting the spring 151 to hold the valve 150 open and the pressure through the 40 pipe 154 again closes the valve 150 through the medium of the diaphragm 153 so that the air is now trapped in the diaphragm chamber 142 to hold the valves 135 and 136 in their operated 45 position and hence, to hold the press closed. The press is opened by exhausting the air from the diaphragm chamber 142 by means of a normally closed spring pressed exhaust valve 156 in a casing 157, which casing is connected by a pipe 158 to the pipe 147 at 159. The valve 156 is operated by a trip lever 160.

In the operation of the construction shown in Figure 8, the operator depresses both push buttons 132, 133 causing the piston in the cylinder 12^a to move the toggle toward straightened position. When the piston passes the port in the casing 98, the air pressure passes through the pipe 149 to the valve casing 148 under the valve 150. The pressure of the spring 151 and of the air pressure built up through the pipe 149 overcomes the pressure on the upper side of the diaphragm 153 permitting the air pressure to pass through the pipe 147 to the diaphragm chamber 142. The diaphragm 143 actuates the stem 144 and lever 145 thereby closing the exhaust valve 136 and opening the intake valve 135 and permitting air to flow from the pipe 138 through the valve casing 134 and pipe 141 to the cylinder 84 to actuate the booster lever 19 or 19^a. When the valves 135, 136 are thus operated the air will 70 pass from the valve casing 134 through the duct 155 to the diaphragm chamber 142 and lock the valves in their operated position. When the operator removes his hands from the push buttons 132, 133, the air pressure below the valve 150 is 75

released so that the diaphragm 153 again closes the valve 150.

In the form shown in Figure 8, owing to the delayed pressure valve in the casing 148, the motor 12^a has delivered all the pressure it can, even though the piston therein has uncovered the port in the casing 98 on the cylinder 12^a. In other words, the motor 12^a continues to deliver pressure until the resistance offered to the head equals that of the power of the motor. In the construction shown in Figures 5, 6 and 7, the power is relayed to the second motor immediately when the piston uncovers the port and the piston in the first cylinder 12 does not necessarily deliver full pressure before the power is relayed to the second cylinder.

In the form shown in Figure 8, owing to the delaying valve 148 a maximum follow-up is provided and the full length of slot 18 is available for the boosting operation and no part of the movement of the piston in this cylinder is wasted in taking up lost motion that would otherwise occur when the head comes down on the work and the piston in the cylinder 12^a has uncovered the port in the casing 98.

In the form shown in Figure 8, the pressure continues to build up the cylinder 12^a and hence further actuates the piston after the piston has uncovered the port in the casing 98, until the pressure is built up in the valve casing 148 sufficiently to open the valve 150 against the diaphragm 153. Hence the first piston and cylinder has delivered practically maximum pressure before the piston in the second cylinder 84 begins to operate.

In the form shown in Figure 7, the check valve 121 is opened at any pressure sufficient to overcome the spring thereof, say 50 pounds, and it will always open at 50 pounds pressure regardless of whether the air pressure in the feed is 60, 70 or 80 pounds etc.

In Figure 8, owing to the diaphragm 153, a balance or relation is maintained between the pressure in the feed line and the pressure at which the valve 150 will open. For instance, assume that when the pressure in the feed line is 60 pounds, per square inch, 50 pounds pressure plus the force of the spring 151 will open the valve. If the pressure varies, say is 70 pounds, it will require 60 pounds pressure plus the force of the spring to open the valve 150.

This invention is particularly advantageous in that a predetermined pressure is always delivered without any attention on the part of the operator regardless of the thickness of the work, or the amount of compression or settling of the padding, or in other words, it is particularly advantageous because it provides for an automatic follow-up mechanism regardless of the thickness of the work and the padding and the amount of compression of the padding.

What I claim is:

1. In a pressing machine, a frame, cooperating pressing elements, one of which is movable toward and from the other, actuating mechanism for the movable element including two sections normally out of coacting relation, one section being movable to close the press and bring said section into effective motion transmitting relation with the other section, and means for actuating the sections successively, the first section being connected to the movable element and the second section including a pry lever pivoted to the frame.

2. In a pressing machine, a frame, cooperating pressing elements one of which is movable toward and from the other, mechanism for actuating

ing the movable element including two sections, one section comprising toggle links pivotally connected together, one link being connected to the movable element and capable of endwise movement relatively to the other link, and the other section comprising a booster lever pivoted to the frame and coacting with the endwise movable link when the toggle straightens, and means for actuating the toggle and the lever successively.

3. In a pressing machine, a frame, cooperating pressing elements one of which is movable toward and from the other, actuating mechanism for the movable element including two sections, one section comprising toggle lines pivotally connected together, one link being connected to the movable element and being movable endwise relatively to the other toggle link and the other section comprising a booster lever pivoted to the frame, the endwise movable link having a shoulder thereon normally out of juxtaposition with said lever and movable into juxtaposition as the toggle straightens during the closing of the press and means for actuating the toggle and the lever successively.

4. In a pressing machine, a frame, cooperating pressing elements one of which is movable toward and from the other, mechanism for actuating the movable element, including two sections, one section comprising toggle links pivotally connected together, one link being connected to the movable element and capable of endwise movement relatively to the other link, and the other section comprising a booster lever pivoted to the frame and coacting with the endwise movable link when the toggle straightens, and means for actuating the toggle and the lever successively, the endwise movable link having a bearing surface, the lever extending at an angle to the straightened toggle and having a face extending lengthwise thereof for coacting with said bearing surface.

5. In a pressing machine, a frame, cooperating pressing elements, one of which is movable toward and from the other, actuating mechanism for the movable element including two sections, one section comprising toggle links pivotally connected together, one being connected to the movable element and being movable endwise relatively to the other toggle link, and the other section comprising a booster lever pivoted to the frame, the endwise movable link having a shoulder thereon normally out of juxtaposition with said lever and movable into juxtaposition as the toggle straightens during the closing of the press, and means for actuating the toggle and lever successively, the lever extending at an angle to the straightened toggle and having an engaging face extending lengthwise thereof and coacting with said shoulder.

6. In a pressing machine, a frame; cooperating pressing elements, one of which is movable toward and from the other; mechanism for actuating the movable element, including two sections, one section including toggle links pivotally connected together, one link being connected to the movable element and capable of endwise movement relative to the other link and provided with a shoulder, and the other section including a booster lever pivoted to the frame and coacting with the endwise movable link when the toggle straightens; means for actuating the toggle and the lever successively; the lever extending at an angle to the straightened toggle and having a face extending lengthwise thereof for coacting with said shoulder, the

shoulder and the face having coacting means to prevent folding of the toggle during the action of the lever.

7. In a pressing machine, a frame, cooperating pressing elements one of which is movable toward and from the other, mechanism for actuating the movable element comprising two sections, one section comprising toggle links pivotally connected together, one link being connected to the movable element and capable of endwise movement relatively to the other link and provided with a bearing surface and the other section comprising a booster lever pivoted to the frame and coacting with the endwise movable link when the toggle straightens, and means for actuating the toggle and the lever successively, the lever extending at an angle to the straightened toggle and having a face extending lengthwise thereof for coacting with said bearing surface, said face extending in an arc concentric with the arc of movement of the joint of the toggle, the bearing surface and the face having coacting means to prevent folding of the toggle during the boosting action of the lever.
8. In a pressing machine, a frame, a buck mounted on the frame, a head movable toward and from the buck, a lever carrying the head, the lever being pivoted to the frame, mechanism for actuating the head comprising toggle links pivoted together and respectively to the frame and to said lever, the link pivoted to the head carrying lever being connected to the other link to have a relative endwise movement and being formed with a bearing surface, a booster lever pivoted to the frame and extending in a general direction parallel to the head carrying lever and having an arc shaped face extending lengthwise thereof and in an arc substantially concentric with the arc of movement of the joint of the toggle, said bearing surface and said arc shaped face being arranged so that the bearing surface slightly clears said arc shaped face during the straightening movement of the toggle and means for straightening the toggle and operating the booster lever successively.

9. In a pressing machine, a frame, a buck mounted on the frame, a head movable toward and from the buck, a lever carrying the head, the lever being pivoted to the frame, mechanism for actuating the head including toggle links pivoted together and respectively to the frame and to said lever, the link pivoted to the head carrying lever being connected to the other link to have a relative endwise movement and being formed with a bearing surface, a booster lever pivoted to the frame and extending in a general direction parallel to the head carrying lever and having an arc shaped face extending lengthwise thereof and in an arc substantially concentric with the arc of movement of the joint of the toggle, said bearing surface and said face being arranged so that the bearing surface slightly clears said face during the straightening movement of the toggle and means for straightening the toggle and operating the booster lever successively, said bearing surface and said face having means for preventing retrograde movement of the toggle links during the boosting action of the booster lever.

10. In a garment or laundry pressing machine, in combination, cooperative pressing elements one of which is movable toward and from the other; operating mechanism for the movable pressing element including, a first fluid operated cylinder and piston motor to initially close the press, and

a second fluid operated motor to apply heavy pressure to the pressing element; operator-operated control means for supplying working fluid to the first motor; pressure operated control means for supplying working fluid to the second motor; and a port line, connected with the cylinder of the first motor in position to be uncovered by the piston after it has completed a portion of its stroke, and connected with the pressure operated control means to supply working fluid for operating said pressure operated control means.

11. In a garment or laundry pressing machine, in combination, cooperative pressing elements one of which is movable toward and from the other; operating mechanism for the movable pressing element including, a first fluid operated motor to initially close the press, and a second motor to apply heavy pressure to the pressing elements; operator-operated control means for supplying working fluid to the first motor; automatic control means for the second motor including mechanism operated by working fluid from the first motor; and conduit means connected with the automatic control means and connected with the first motor in position to receive working fluid from the first motor when said first motor has operated a predetermined distance in moving the press toward preliminary closed position.

12. In a garment or laundry pressing machine, in combination, cooperative pressing elements one of which is movable toward and from the other; operating mechanism for the movable pressing element including, a first fluid operated cylinder and piston motor to initially close the press, and a second fluid operated motor to apply heavy pressure to the pressing elements; operator-operated valve means for controlling the supply of working fluid to the first motor; pressure operated valve means for controlling the supply of working fluid to the second motor; and a port line, connected with the cylinder of the first motor in position to be uncovered by a piston after it has traveled substantially the distance necessary to initially close the press, said port line being also connected with the pressure operated valve means so as to supply working fluid for operating said pressure operated valve means.

13. In a pressing machine, cooperating pressing elements, one of which is movable toward and from the other, actuating means therefor including a pair of successively operable, fluid operated motors, a feed system, operator-operated valve means for controlling the flow of motive fluid from said system to the first motor, automatic valve means for controlling the flow of motive fluid from said system to the second motor and a delayed pressure valve in the system between the first motor and the control means for the second motor, said delayed valve means including a casing, a movable pressure member in the casing, the casing on one side of the member being connected to the feed system, a valve in the casing, a spring acting on the valve tending to open it against the movable member in the valve casing, a pipe connecting the valve casing from a point below the valve to the first motor and a pipe connecting the valve casing from a point between the movable member in the valve casing and the valve therein to the operating means for the second motor.

14. A garment or ironing press comprising a frame, cooperative pressing jaws, one of which is movable with respect to the other to open and close the press, actuating mechanism for the movable pressing jaw including an extensible

- toggle, a booster lever pivoted on the frame and having a wedge-shaped face extending longitudinally thereof, means for closing the press and moving the toggle toward substantially straightened position with a portion thereof overlying one end of the booster lever, a V-slot on the overlying portion of the toggle for engaging the wedge-shaped face of the booster lever, and means to operate the booster lever to thrust 5 against the V-slot to extend the toggle and apply heavy pressure to the pressing elements.
15. A garment or ironing press comprising co-acting press jaws, one of which is movable toward and from the other, means for actuating the movable jaw including a toggle having an endwise movable portion, means for straightening the toggle, booster means for moving said portion endwise when the toggle assumes a substantially straightened position, said booster means and the 20 endwise portion having complementary wedge-shaped engaging faces.
16. A garment or ironing press comprising co-operating pressing elements one of which is movable toward and from the other, actuating means therefor including a pair of successively-operable pressure-operated motors, operator-operated means for controlling the flow of motive fluid to the first motor, automatic means for controlling the flow of motive fluid to the second motor upon 25 a predetermined extent of movement of the actuating means, and means for delaying the operation of the automatically operated means for a period after the actuating means has completed the predetermined extent of movement.
- 30 17. A garment or ironing press comprising co-operating pressing elements one of which is movable toward and from the other, actuating means therefor including a pair of successively-operable pressure-operated motors, operator-operated valve means for controlling the flow of motive fluid to the first motor, automatic valve means for controlling the flow of motive fluid to the second motor upon a predetermined extent of movement of the actuating means, means for 35 delaying the operation of the automatically operated valve means for a period after the first motor has been actuated the predetermined extent of movement, means for automatically locking the operator-operated valve means in its operated position, and operator-operated valve releasing means.
- 40 18. A garment or ironing press comprising co-operating pressing elements one of which is movable toward and from the other, actuating means therefor including a pair of successively-operable pressure-operated motors, operator-operated valve means for controlling the flow of motive fluid to the first motor, automatic valve means for controlling the flow of motive fluid to the 45 second motor upon a predetermined extent of movement of the actuating means, means for delaying the operation of the automatically operated valve means for a period after the actuating means has been actuated the predetermined extent of movement, pressure operated means controlled by the delaying means for locking the operator-operated valve means in operated position, and operator-operated means for releasing all of said valve means.
- 50 19. A garment or ironing press comprising co-operating pressing elements one of which is movable toward and from the other, actuating means therefor including a pair of successively-operable motors, operator-operated means for controlling the operation of the first motor, auto-

5 matic means for controlling the operation of the second motor upon a predetermined extent of movement of the actuating means, and means controlled by the pressure in the first motor for delaying the operation of the automatically operated means controlling the second motor for a period after the first motor has moved the predetermined extent of movement and delivered a predetermined pressure.

20. A garment or ironing press comprising co-operating pressing elements one of which is movable toward and from the other, actuating means therefor including a pair of successively-operable pressure-operated motors having movable members, operator-operated valve means for controlling the flow of motive fluid to the first motor, automatic valve means for controlling the flow of motive fluid to the second motor upon a predetermined extent of movement of the actuating means, including means controlled by the pressure in the first motor for preventing the operation of the automatic valve means controlling the second motor for a period after the actuating means has moved the predetermined extent of movement and until the resistance offered to the movable pressing element is sufficient to cause the pressure in the first motor to build up to a predetermined degree and means for holding the press closed and for controlling the opening thereof.

30 21. A garment or ironing press comprising co-operating pressing elements one of which is movable toward and from the other, actuating means therefor including a pair of successively-operable fluid-operated motors, operator-operated valve means for controlling the flow of motive fluid to the first motor, automatic valve means for controlling the flow of motive fluid to the second motor, including means to prevent operation of the automatic valve means until after the first 40 motor has moved a predetermined distance, and a delayed pressure valve between the first motor and the control means for the second motor.

22. An actuating mechanism comprising fluid operated motors each having a movable power 45 member, a feed pipe for a motive fluid having branches leading to the motors respectively, control valve means in each branch, manual means for operating the control valve means in one branch, pressure operated means for operating 50 the control valve means in the other branch, means connected with the pressure operated means and controlled by the movable member of that motor which is controlled by the manual means for controlling a flow of fluid to and from 55 the pressure operated means, and means to release the pressure in the motors.

23. An actuating mechanism including fluid operated motors, a feed pipe for a motive fluid having branches leading respectively to the motors, one of the motors comprising a cylinder and a piston movable therein, a control valve means in each branch, manual means for operating the control valve means in the branch leading to the cylinder and pressure operated means for operating the control valve means in the other branch, an intake and exhaust pipe for the pressure operated means, a port in the side of the cylinder arranged to be uncovered by the piston during the movement of the piston, said intake and exhaust pipe being connected to the port and hence to the feed pipe through the cylinder.

24. An actuating mechanism comprising fluid operated motors, a movable member for each motor, a feed pipe for a motive fluid having 75

- branches leading respectively to the motors, control valve means in each branch, manual means for operating the control valve means in one branch, pressure operated means for operating 5 the control valve means in the other branch, a second pressure operated means for holding the manual control means in its operated position, the second pressure operated means having an intake and exhaust pipe, means controlled by 10 the movement of the movable member of that motor which is controlled by the manual means for controlling the flow through said intake and exhaust pipe, an intake and exhaust pipe for the first pressure operated means connected to the 15 intake and exhaust pipe of the second pressure operated means, and means to exhaust the motors.

25. An actuating mechanism comprising fluid operated motors, one of which comprises a cylinder and a piston movable therein, a feed pipe for the motive fluid having branches leading to the motors respectively, control valve means in each branch, manual means for operating the control valve means in the branch supplying the cylinder, and pressure operated means for operating the control valve means in the other branch, a second pressure operated means for holding the manually operated control means in its operated position, a combined intake and exhaust conduit leading to the second pressure operated means and also connected to the first pressure operated means, the cylinder having a port on one side thereof arranged to be passed by the piston, to be controlled thereby and the intake and exhaust conduit connecting with the port, and means to exhaust the motors.

26. An actuating mechanism comprising fluid operated motors, one of which comprises a cylinder and a piston movable therein, a feed pipe for the motive fluid having branches leading to the motors respectively, control valve means in each branch, manual means for operating the control valve means in the branch supplying the cylinder, pressure operated means for operating 45 the control valve means in the other branch and for holding the manually actuated control valve means in its operated position, a combined intake and exhaust conduit connected with the pressure operated means, the cylinder having a port on one side thereof arranged to be passed by the piston to be controlled thereby and the intake and exhaust conduit connecting with the port, and means for releasing the fluid in said pressure operated means.

55. 27. An actuating mechanism comprising fluid operated motors, each having a movable power member, a feed pipe for a motive fluid having branches leading to the motors respectively, control valve means in each branch, manual means 60 for operating the control valve means in one branch, and pressure operated means for operating the control valve means in the other branch and connected with a source of fluid pressure, and means controlled by the movable member 65 of that motor controlled by the manual means for controlling the flow of fluid to and from the pressure operated means, and means for releasing the motive fluid in the pressure operated means.

70. 28. An actuating mechanism comprising fluid operated motors, a movable member for each motor, a feed pipe for a motive fluid having branches leading respectively to the motors, control valve means in each branch, manual means 75 for operating the control valve means in one

branch and pressure operated means for operating the control valve means in the other branch, a second pressure operated means for holding the manual control means in its operated position, the second pressure operated means having an intake and exhaust pipe, means controlled by the movement of the movable member of that motor which is controlled by the manual means for controlling the flow through said intake and exhaust pipe to operate the second pressure operated means, an intake and exhaust pipe for the first pressure operated means connected to the intake and exhaust pipe of the second pressure operated means, and means for releasing the motive fluid in the first and second pressure operated means.

29. An actuating mechanism for a garment or ironing press comprising a first and second fluid operated motor, the first motor including a cylinder and a piston movable therein, a control valve means connected with each motor, manual means for operating the control valve means for the first motor, pressure operated means for operating the control valve means for the second motor to feed fluid thereto, means controlled upon a predetermined extent of movement of the piston of the first motor for connecting the pressure operated means to a source of fluid pressure whereby the control valve means for the second motor is operated, and means to exhaust the motors.

30. An actuating mechanism for a garment or ironing press comprising a first and second fluid operated motor, the first motor including a cylinder and a piston movable therein, a control valve means connected with each motor, manual means for operating the control valve means to the first motor, pressure operated means for operating the control valve means to the second motor, a port in the side of the cylinder of the first motor arranged to be uncovered by the piston during the movement thereof, means connecting the port to the pressure operated means, and means to exhaust the motors.

31. An actuating mechanism for a garment or ironing press comprising a first and second fluid operated motor having movable members, control valve means connected with each motor, manual means for operating the control valve means to the first motor, pressure operated means 50 for operating the control valve means to the second motor, a second pressure operated means for holding the manually operated control means in its operated position, means operated by the movement of the movable member for the first 55 motor for controlling the flow of motive fluid to the two pressure operated means whereby the manually operated control means are held in operated position and the control valve means for the second motor is operated, and means to exhaust the motors.

32. An actuating mechanism for a garment or ironing press comprising a first and second fluid operated motor one of which comprises a cylinder and a piston movable therein, control valve means connected with each motor, manual means for operating the control valve means to the first motor, pressure operated means for operating the control valve means to the second motor, a second pressure operated means for holding the 70 manual means in its operated position, the cylinder having a port therein connected with the two pressure operated means and passed by the piston to deliver motive fluid to both pressure operated means whereby the manually operated 75

control means are held in operated position and the control valve means for the second motor is opened, and means to exhaust the motors.

33. An actuating mechanism for a garment or ironing press comprising a first and second fluid operated motor one of which includes a cylinder and a piston movable therein, control valve means connected with each motor, manual means for operating the control valve means for the first motor, pressure operated means for operating the control valve means for the second motor, a second pressure operated means for holding the manually operated control valve means in its operated position, the cylinder having a port therein connected with the two pressure operated means and passed by the piston to deliver motive fluid to both pressure operated means whereby the manually operated control means are held in operated position and the control valve means for the second motor is opened, and

means for releasing the fluid in said pressure operated means.

34. An actuating mechanism comprising fluid operated motors, each having a movable power member, a feed pipe for a motive fluid having branches leading to the motors respectively, control valve means in each branch, manual means for operating the control valve means in one branch, and pressure operated means for operating the control valve means in the other branch, an intake and exhaust pipe for the pressure operated means connected in communication with the feed pipe, and means controlled by the movable member of that motor controlled by the manual means for controlling the flow of fluid to and from the pressure operated means, and means for releasing the motive fluid in the motor controlled by the manual means and the pressure operated means.

ERNEST DAVIS. 20
